UNITED STATES PATENT OFFICE.

HAROLD J. CARMODY, OF NEW YORK, N. Y., ASSIGNOR OF ONE-THIRD TO JOSEPH M. LEVINE AND ONE-THIRD TO HARRY UFLAND, OF NEW YORK, N. Y.

FIRE-EXTINGUISHER.

1,162,133.

Specification of Letters Patent. Patented Nov. 30, 1915.

Application filed July 11, 1914. Serial No. 850,518.

To all whom it may concern:

Be it known that I, HAROLD J. CARMODY, a citizen of the United States, residing in the city of New York, borough of Brooklyn, in the county and State of New York, have invented certain new and useful Improvements in Fire-Extinguishers, of which the following is a specification.

My invention relates to fire extinguishers of the type in which a chemical liquid is discharged by air pressure my purpose being to increase the efficiency of the extinguisher and more particularly to accomplish the following results:—I. To render the air pressure, used for ejecting the fire extinguishing liquid independent of the quantity of such liquid contained within the extinguisher. II. To provide the extinguisher with a pump of special form, so that it may serve the double purpose of forcing the fire extinguishing liquid into the extinguisher and of creating within the extinguisher an air pressure for ejecting the liquid. III. To provide for reaching and ejecting the liquid within the extinguisher, even if only a small quantity be present. IV. To give the discharge outlet and parts immediately associated therewith such form and location as to enable the operator to vary, within wide limits, the character of the discharge. V. To provide the body portion of the extinguisher with a funnel-shaped head for receiving the liquid and placing the same under control of the pump in order to enable the pump to force the liquid into the extinguisher. VI. To provide the pump, forming a part of the extinguisher mechanism, with a piston which is expanded positively during compression, and without having been previously moistened. VII. To provide the extinguisher with a number of improved parts, including a needle valve requiring no packing and no expanding or jam nuts, and also a bayonet lock for normally holding the pump plunger in a predetermined position relatively to the pump barrel and adjacent parts.

Reference is made to the accompanying drawing forming a part of this specification, and in which like letters indicate like parts.

Figure 1 is a side elevation of the extinguisher, certain parts being broken away. Fig. 2 is a substantially centrally vertical section through the extinguisher complete.

Fig. 3 is a section on the line 3—3 of Fig. 55 2, looking in the direction of the arrow.

A container having generally the form of a cylinder is shown at 4, and serves as a casing or body member for holding the other parts. The bottom of the container 4 60 is closed by a head 5, the latter being provided with a rounded portion 5^a, as may best be understood from Fig. 2. The upper end of the container carries a top head 6, having generally the form of a funnel, and 65 adapted to serve as such. Integral with the top head 6 is an annular flange 7, which fits neatly around the adjacent end portion of the container. The top head 6 is of a generally annular form and carries a barrel 8 70 which has a cylindrical form and is concentric with the container 4. The barrel 8 reaches nearly to the bottom of the container, and carries at its lower end a screw plug 9 provided with a plunger seat 10, the 75 latter being simply cored out and ground. A check valve 11 is carried by the screw plug 9 and seated within the same, so as to extend up into the plunger seat. A valve spring 12 engages the valve 11 and tends to 80 hold the latter against its seat. A spider 13 or analogous support engages the spring 12. A flexible duct 14 having the form of a corrugated metallic tube is secured upon the lower end of the screw plug 9, which is reduced for this purpose as will be understood from Fig. 2. In this manner the flexible duct 14 is mounted upon the lower end 85 of the barrel 8. The flexible duct may be bent by its own weight, whenever the container 4 is tilted to one side, and when the duct 14 is thus bent, it tends to hang into the portion of the container carrying any small quantity of liquid therein remaining. The container 4 is adapted to hold a quantity of fire extinguishing liquid 15, which may be, for instance, carbon tetra chlorid. The upper end of the barrel 8 is fitted with a spider 16, the latter being provided with holes 17 for facilitating the introduction of 90 100 the fire extinguishing liquid.

A pair of cleats 18 each of arcuate form are secured upon the top head 6 and disposed upon opposite sides of the barrel 8.

A plunger rod is shown at 19 and has a 105 substantially tubular form. This plunger rod carries a ring 20 and extending from opposite sides of this ring are two wings 21

of arcuate form. These wings are provided with inwardly extending portions 21^a so positioned that they may extend into and slightly beneath the cleats 18, thus forming 5 a so-called breech block joint or connection between the plunger rod 19 and the cleats 18. The plunger rod is provided with a portion 22 which is carefully ground and adapted to fit into the plunger seat 10. The lower 10 end of the plunger rod 19 carries a spider 23, the latter being so positioned that when the plunger rod is in its lowermost position the spider 23 holds the valve member 11 away from its seat, or in other words, holds the 15 valve open.

Fitted loosely upon the plunger rod 19 is a sleeve 24 which is threaded externally. A cork ring 25 is fitted upon this sleeve. A leather cup 26 encircles the cork ring 25 20 and is held in position by aid of a nut 27. Another nut 28 like the nut 27 is mounted upon the sleeve 24. By turning these nuts 27, 28 any desired degree of pressure may be applied to the cork ring. The plunger 25 rod 19 carries a snap ring 29 detachably secured to it and located just above the ground portion 22. Another flange 30 of annular form is carried by a sleeve 31, the latter encircling and being secured rigidly 30 upon the plunger rod 19. A space 24^a is provided between the upper end of the sleeve 24 and the adjacent surface of the flange 30, and the sleeve 24 loosely encircles the plunger rod 19. The sleeve 24, at 35 its lower end, is provided with notches 24^b. In any event, there should be room for a liquid to pass freely between the outer surface of the plunger rod 19 and the inner surface of the sleeve 24. Encircling the plunger rod 19 is a gasket or packing 32 of leather, so located as to close the space between the sleeve 24 and the rod 19 whenever the plunger rod is raised.

The upper end of the plunger rod 19 is 45 provided with a cylindrical casing 33, and extending through this casing is a passage 34. A needle 35 extends into this passage, and is provided with a handle 36 whereby it may be turned. The needle is further provided with an enlarged threaded portion 37, fitting into the adjacent end portion of the casing 33. The middle portion of the needle fits fluid-tight within the passage. The casing is also provided with a conical inner surface 34^a, and the needle 35 carries a conical point 34^b which fits into the conical inner surface 34^a. The casing 33 is provided with a branch passage 34^c, which extends into the conical space adjacent thereto, as shown 50 in Fig. 1. An orifice 38 merges into the chamber 34, which is merely a clearance passage to avoid undue friction. The construction of the casing 33 is such that the liquid can not enter the casing except through the 60 branch passage 34^c, and is unable to escape 65

at the right according to Fig. 2, owing to the fluid-tight fit of the needle within the casing. The flow of liquid out of the orifice 38 is under complete control of the needle. The discharge may be given the 70 form of either a stream or a spray, as desired, this purpose being facilitated by the fact that the needle valve, controlling the discharge, is located at the extreme point of exit of the liquid. The control of the 75 discharge is thus rendered local, and, because of this fact the form of the discharge may be varied within wide limits. The operator by grasping the casing 33 and treating it as a handle can cause the tubular plunger rod 80 19 to reciprocate, and thus act as a pump plunger. By forcing it downward into its lowermost position the ring 20 is brought adjacent the cleats 18, so that the inwardly extending portion 21^a of the sleeve 21 may, 85 by a partial turn of the casing 33, be brought into engagement with the cleats 18, thus locking the plunger rod in its lowermost position.

Each time the plunger rod 19 is thus 90 locked at the lower limit of its travel according to Fig. 2, the check valve 11 is engaged by the spider 23 and forced downwardly. When the plunger rod 19 is locked in its lowermost position as above described, 95 by the breech block connection, there is free communication between the interior of the container 4 and the interior of the tubular plunger rod 19. In other words, the check valve is open, and the liquid 15, which is normally under pressure, is free to travel upwardly through the tubular plunger rod 19, provided the needle valve 35 of the top is open. Therefore, the operator by manipulating the needle valve can control the 100 discharge of the liquid from the orifice 38.

In order to introduce the liquid 15, a quantity of it is poured into the top head 6, serving as above described as a funnel. Upon the upstroke of the plunger 19 the liquid is by suction drawn down between the sleeve 24 and the outer surface of the plunger rod 19 and thus deposited within the lower portion of the barrel 8. The downstroke of the plunger causes the leather gasket 32 to lodge upon the upper end of the sleeve 24, so as to prevent the liquid from flowing upwardly, and also causes the leather cup 26 and cork ring 25 to act as a liquid-tight packing, and thus to force the liquid down past the check valve 11. The parts within the barrel 8, together with this barrel, therefore serve as a pump for introducing the fire extinguishing liquid within the container 4 which usually contains air, 110 under pressure. The sleeve 24 and parts adjacent thereto perform a function analogous to that of a check valve. That is to say, upon the downstroke of the plunger rod 19 the packing 32 closes the upper end of the 115 120 125 130 135 140 145 150 155 160 165 170 175 180

cylindrical passage 24^a, but upon the up-stroke of the plunger rod the cylindrical passage 24^a is left open. The lower end of the passage 24^a is never closed, owing to the presence of the notches 24^b. The cork ring 25 and leather cup 26 together constitute a packing such as may always be depended upon to fit the interior of the barrel 8 under all conditions. If the leather cup 26 or the cork ring 25 be worn, for instance, or if they be dry, they will nevertheless fit fluid-tight, and even air tight, as soon as the plunger rod 19 makes one or two strokes. This is because the leather cup 26 is acted upon by the liquid, or by the compressed air, as the case may be, and thus expanded positively to fit the interior of the pump barrel.

As may be readily understood from the foregoing description, the filling of the extinguisher with either liquid or air takes place through the pump. The needle valve control of the discharge enables the character of the discharge to be varied, say to form a stream or a spray, at the will of the operator. The funnel shaped head 6 facilitates introduction of the liquid by aid of the pump. The needle valve, because of its form, requires neither packing, expansion nuts nor jam nuts. The bayonet lock, consisting of the parts 18, 21 and 21^a, normally holds the pump plunger rigidly in its lower-most position. If, now, after the introduction of the liquid as just described, or at any other time, the plunger rod 19 be reciprocated by hand as above described, the device works as an air pump, and forces compressed air into the container. Even if the container has very little of the liquid in it, the air pressure may nevertheless be produced as desired. For purposes of the pump, the cork ring 25 and leather cup 26 together serve the purpose of a valvular piston.

I do not limit myself to the precise construction shown, as variations may be made therefrom without departing from the spirit of my invention.

Having thus described my invention, I claim:—

1. In a fire extinguisher the combination of a container provided with an inwardly cupped head serving as a funnel for holding a liquid, a pump secured to said head and extending into said container for the

purpose of receiving the liquid from said funnel and forcing the same into said container, said pump also serving as an air pump for compressing air into said container if operated while said funnel is empty, and means for discharging said liquid through said pump, by pressure of said air within said container.

2. In a fire extinguisher the combination of a container for holding a liquid and a volume of air under pressure, a pump extending into said container for filling said liquid and said air into said container, said pump being provided with a hollow plunger rod and handle, and a needle valve carried by said handle for discharging the liquid from said container in the form of a stream or a spray, as desired.

3. In a fire extinguisher the combination of a container provided with an inwardly cupped head serving as a funnel for holding a liquid, a pump extending into said container and connected with said head for the purpose of receiving the liquid from the funnel and forcing the same into said container, said pump also serving as an air pump for compressing air and forcing the same into said container if operated while said funnel is empty, said pump having a movable plunger, and a bayonet joint for normally holding said plunger in a predetermined fixed position relatively to said container.

4. In a fire extinguisher the combination of a container provided with a member serving as a funnel for holding a liquid, a pump extending into said container and connected with said funnel for receiving the liquid from the funnel and forcing the same into said container, said pump also serving as an air pump for compressing air and forcing the same into said container if operated while said funnel is empty, said pump having a movable plunger of tubular form and a handle mounted upon said plunger for actuating the same, and a needle valve carried by said handle for controlling a discharge of liquid from said container, said needle valve being made entirely of metal.

HAROLD J. CARMODY.
